INVENTOR

Louis W. Kruse
BY John A. Chaismith
HIS ATTORNEY

UNITED STATES PATENT OFFICE.

LOUIS W. KRUSE, OF SAN JOSE, CALIFORNIA.

COUPLING.

1,422,991.

Specification of Letters Patent.

Patented July 18, 1922.

Application filed January 9, 1920. Serial No. 350,379.

To all whom it may concern:

Be it known that I, LOUIS W. KRUSE, a subject of the King of Great Britain, and a resident of San Jose, in the county of

5 Santa Clara and State of California, have invented certain new and useful Improvements in Couplings, of which the following is a specification.

10 My invention relates particularly to a coupling to be used in connection with the wiring system of automobiles.

In the latest model of the Ford automobile the wires leading to the commutator distributor and one headlight are carried 15 from their respective terminals to the said distributor and the said headlight through a conduit, the front end of the conduit terminating at a point near the front end of the engine and the several wires being exposed from that point to their several connections. Those wires running from the conduit to the distributor, four in number, are exposed to oil drippings from working parts and to injury by the 20 engine fan or the fan belt. When the insulation upon any one of these wires is injured materially the particular wire exposed cannot be removed alone but the whole conduit with all or the wires passing 25 through it from one terminal to another must be removed and discarded.

It is the object of my invention to provide a simple and easily installed coupling for the above mentioned wires at a point 30 adjacent the front end of the conduit so that but a short section of any injured wire need be removed and replaced, thereby saving the expense attached to installing an entirely new conduit and wires.

35 In the drawing:—

Figure 1 is a diagrammatical illustration of a wiring system embodying my invention.

Figure 2 is a side elevation of my improved coupling.

40 Figure 3 is a sectional view on line 3—3 of Figure 2.

Figure 4 is an end elevation of the coupling with the cap removed.

45 Referring now more particularly to the drawing, at 1—2—3—4—5—6 are shown a plurality of wires extending from their respective terminals 1^a—2^a—3^a—4^a—5^a—6^a on an automobile body to their respective terminals 1^b—2^b—3^b—4^b—5^b—6^b as shown, 50 the terminals 1^b—2^b—3^b—4^b being mounted on the distributor and the terminals 5^b—6^b

being mounted in the headlight 7. These several wires are shown as enclosed throughout the major portion of their length within a conduit 8.

At 9 I show the body portion of my improved coupling made of insulating material and of suitable length and diameter having an annular ring 10 formed on the central portion thereof to form shoulders 11. Over 60 each end of body portion 9 and engaging one shoulder 11 is a cap member 12 held in position in any suitable manner as by threading thereon as at 13. Each cap member 12 is provided with an orifice 14 of 65 sufficient size to permit the passage of the said six wires therethrough. Bored through body portion 9 and parallel with the axis thereof and concentrically arranged with relation to said axis are six holes as 1^c—2^c—75 3^c—4^c—5^c—6^c, each hole having a tube as 1^d—2^d—3^d—4^d—5^d—6^d of electricity conducting material inserted therein as shown. A screw is set into the side of each end of each tube as shown at 1^e—2^e—3^e—4^e—5^e—6^e. 80

In installing this coupling the several wires are cut at a point adjacent the forward end of conduit 8. The ends of the several wires 1—2—3—4—5—6 projecting from the end of conduit 8 are carried 85 through orifice 14 in one cap member 12 and each wire inserted into one of the tubes 1^d—2^d—3^d—4^d—5^d—6^d and secured therein by the screw set therein, the cap 12 being then firmly fixed in position. 90

In like manner the severed ends of the remaining parts of said wires are secured in position in their respective tubes in the coupling.

The wires 5 and 6 to headlight 7 are 95 seldom if ever injured and therefore may not need repairing. But if any one of the wires extending to the distributor should be injured sufficiently to require removal, the whole system of wires need not be replaced, but the injured section may be removed from its connection to the starter and to the coupling and replaced with a new section at an insignificant expense of either time or money. 100

105 It is understood of course that changes in form, proportions and construction may be made within the scope of the appended claim.

I claim:—

110 A coupling comprising a cylindrical body portion of insulating material provided with

oppositely directed shoulders, and a cap member of insulating material adapted to engage each shoulder and provided with an orifice in the end thereof to permit the passage of wires therethrough, said body portion having a plurality of holes formed longitudinally therein and concentric to the

axis thereof, a tube of electricity conducting material positioned in each hole, and a screw operatively positioned with relation to each end of each tube and adapted to engage the end of a wire inserted therein.

LOUIS W. KRUSE.
